[57] CLAIM

The ornamental design for a fishing vest with integral
hood, as shown.

DESCRIPTION

FIG. 1 is a top, front, right perspective view of a fishing
vest with integral hood showing my new design;
FIG. 2 is a front view of the vest with hood extended
and flat folded;

FIG. 3 is a perspective view of the vest showing the
front and bottom edge thereof with the hood extended
and flat folded; and

FIG. 4 is a perspective view showing the back, left side
and top portion with the hood extended and flat folded.

FIG. 1

FIG. 3

FIG. 2

FIG. 4
